ATTORNEY.

UNITED STATES PATENT OFFICE.

ARTHUR C. CARR, OF SAN FRANCISCO, CALIFORNIA.

CIGAR AND CIGARETTE CASE.

1,220,496.

Specification of Letters Patent. Patented Mar. 27, 1917.

Application filed March 20, 1915. Serial No. 15,705.

To all whom it may concern:

Be it known that I, ARTHUR C. CARR, a citizen of the United States of America, residing at 445 O'Farrell street, in the city and county of San Francisco, in the State of California, have invented certain new and useful Improvements in Cigar and Cigarette Cases, of which the following is a specification.

10 My invention relates to new, useful and novel improvements in cigar and cigarette cases and has as its primary object and feature that of a case provided with an ejector adapted to eject or pass from the case a single cigar or cigarette in such a manner that the smoker may easily and readily remove it, or may pass the cigar or cigarette from the case to his mouth without touching it with his hand and without opening the case. It is equally applicable to a portable pocket case and to a stationary or stand case, and for both cigars and cigarettes. The principle of the invention being identical in each instance, the pocket cigarette case 25 only is described and shown in the specification and drawings.

Finally the object of the invention is to provide a device of the character described that will be strong, durable and efficient, 30 simple and comparatively inexpensive to construct, also one in which the several parts will not be liable to get out of working order.

With the above and other objects in view, 35 the invention has relation to a certain arrangement and combination of parts, an example of which is described in the following specification, pointed out in the appended claims and illustrated in the accompanying drawings, wherein:

Figure 1 is a perspective view of the case showing, in this instance, a cigarette projecting from the case.

Fig. 2 is a plan view of the case shown 40 open.

Fig. 3 is a cross sectional view of the case, showing the construction of the ejector member.

Referring now more particularly to the 45 drawings, wherein the same reference characters denote similar parts throughout the several views,

The numeral 1 designates one section of a case, in this instance the lower portion or 50 container of a cigarette case, the same being provided with the usual form of hinged

cover or lid 2 adapted to tightly close the case.

An opening 3 of sufficient dimensions to permit the free passage of a cigarette or other object to be ejected, is provided in the end wall of the container portion 1 of the case. A pair of flap like stops 4 or closures are hinged to the walls of the case at 4^a on either side of the opening. Coiled pressure springs 5 are adapted to hold the stops normally in alinement with the end wall of the case and to form a part thereof.

In their normal or closed position the stops are designed to prevent the cigarettes 70 from falling through the exit opening and when in operation they are adapted to swing outwardly under pressure of the cigarette when forced forward by the ejector member allowing the cigarette to pass between the 75 stops which, through the action of the springs 5, exert sufficient pressure upon opposite sides of the cigarette to prevent it from falling from the case or being returned into the case by the retraction of the ejector, 80 thus holding the cigarette in its extended position as illustrated in Fig. 1, where it may be easily and readily removed with the hand or lips.

A slot 6 is provided in one section of the 85 case. An ejector member 7 is contained within the case and slidably confined within the slot 6. The ejector member has formed integrally therewith a loop or curl 8 which occupies sufficient space in the one corner of 90 the case to displace or keep back one cigarette from over and adjacent the path of travel of the cigarette which is to be ejected, and also acts as a feed, keeping the cigarettes from becoming crossed and ledged in the 95 case. This insures an accurate and single passage of the one cigarette C from the case.

A thrust bracket 9 is formed on the ejector member and turned back, adapted to lie contiguous with the wall of the case and 100 behind the end of the cigarette C to be projected from the case. A coil spring 10 has one extremity fixed to the forward extremity of the ejector member and the other to a wall of the case and serves to return the 105 ejector to its normal position, after the same has been displaced.

A thumb or finger slide 11 is formed integral with the ejector and lies contiguous with the exterior surface of the case and 110 conveniently located where one may readily press against the slide causing the ejector to

pass a cigarette, cigar or other similar object through the spring closed opening.

The opening through which the cigarettes are passed is here closed with a pair of hinged flap covers or doors, as indicated, which are adapted to open under the pressure of the moving cigarette, and also to hold the cigarette with sufficient tension to prevent it from falling from or returning 10 into the case.

The case, in this instance, is shown containing several cigarettes. When in use the operator will turn the case on edge, as Fig. 1, which will cause a cigarette to roll into 15 position and in front of the thrust bracket ready for delivery through the opening.

The invention is presented as including all such modifications and changes as properly come within the scope of the following 20 claims.

What I claim is:

1. In a cigarette case, the combination of a case provided with an opening therein, of a spring actuated closure adapted to close 25 the opening, of a case of proportions to hold a double row of cigarettes, an ejector member confined within a slot formed in the case, and a loop formed on the ejector member adapted to displace one cigarette thereby 30 causing the ejector member to eject one cigarette only or other matter to be ejected at each operation of said ejector.

2. In a carrying receptacle, the combination with a case provided with an opening 35 formed in the wall thereof, said case formed of such proportions as to contain a double row of cigarettes, an ejector member contained in the case and being confined in an elongated slot formed in said case, of an 40 ejector bracket formed on the ejector member adapted to be in contact with one extremity of the cigarette, a pair of closure members pivoted to the case and adapted to close the aforesaid opening, and a spring

lying in contact with each closure adapted 45 to close said opening after the ejected cigarette has passed through.

3. In a carrying receptacle, the combination with a case adapted to contain a double row of cigarettes, of an ejector member 50 slidably confined in a slot formed in said case, said ejector member adapted to lie in contact with the first cigarette of the bottom row, and a curl or loop formed on said ejector adapted to exclude the first cigarette of 55 the top row from assuming a position directly over the first cigarette of the bottom row.

4. In a carrying receptacle or case for cigarettes or other matter, the combination 60 with a case provided with an opening, of a pair of spring pressed closures pivoted in the opening, an ejector member contained in the case and in direct line with the closures, said ejector member adapted to 65 pick up and eject only one cigarette at a time ejecting same partly through the opening against the closures, and said closures adapted to grasp the cigarette and hold same in position after the ejector has re- 70 turned to its normal position.

5. In a cigarette case, the combination of a container adapted to hold a double row of the objects contained therein, of a spring 75 closed closure provided in an opening formed in the container and adapted to normally close the opening, and an ejector device slidably contained in the case and adapted to admit only one cigarette to pass into position before and in the path of the 80 opening and the closures.

In testimony whereof I affix my signature in the presence of two witnesses.

ARTHUR C. CARR.
